HYDROCARBON CONVERSION PROCESS

Filed Dec. 20, 1947

UNITED STATES PATENT OFFICE

2,487,795

HYDROCARBON CONVERSION PROCESS

Louis P. Evans, Woodbury, N. J., assignor to Socony-Vacuum Oil Company, Incorporated, a corporation of New York

Application December 20, 1947, Serial No. 793,000

8 Claims. (Cl. 196—52)

1

This invention pertains to a process for conversion of high boiling hydrocarbons at controlled elevated temperatures in the presence of a particle-form contact mass material. This invention is particularly concerned with a process for the conversion of hydrocarbon feed stocks which contain both asphaltic and oily constituents.

Such conversion processes may involve treating, reforming, polymerization, oxidation, desulphurization, cracking, etc., of the hydrocarbons. A particularly important process is the catalytic cracking conversion of hydrocarbons, it being well known, for example, that hydrocarbon fractions boiling above the gasoline boiling range may be converted to lower boiling gasoline containing hydrocarbons upon being subjected to contact with a suitable solid porous catalyst at temperatures of the order of 800° F. and upwards and at pressures usually above atmospheric.

Heretofore, such conversion processes have been limited to the conversion of a relatively light, clean, substantially tar or asphalt free petroleum feed stocks because of the tendency of the asphalt containing stocks to cause the formation of excessive deposits of coky contaminants on the catalyst which deposits cannot be economically removed. In order to avoid these heavy coke deposits which render the cracking process unfeasible, it has been the wide refinery practice to subject some high boiling petroleum feed stocks (when available with a broad boiling range) to a preliminary tar separation step, separate an easily vaporizable fraction from a liquid fraction which bears the asphaltic constituents and to subject only the vaporizable fraction to catalytic cracking while discarding the liquid tar separator bottoms. Since this discarded fraction may be made up of a large proportion of valuable oily constituents and a smaller proportion of asphaltic constituents, it is obvious that a large quantity of otherwise acceptable catalytic cracking feed stock is lost and unavailable as such in the prior art tar separator operation. When the crude residuum is not of such boiling range and does not contain substantial amounts of vaporizable gas oil, it has been considered in practice as being unsuitable as such for a cracking charge stock. The problem is becoming increasingly serious due to the fact that relatively low boiling petroleum crudes are becoming less plentiful and the crudes which are most readily available are high boiling crudes in which the oily constitu-

2

ents boil so high as to prevent their separation from asphaltic constituents by distillation process without subjecting them to temperatures at which undesirable thermal cracking and excessive coking occur. As a result, in order to use such high boiling stocks at all, it is necessary first to subject them to a preliminary thermal coking step to provide some lower boiling oily fractions for a subsequent catalytic cracking operation.

10 By-products from the coking process are a heavy liquid cut which may contain a substantial amount of oily constituents as well as asphaltic constituents and a very large amount of petroleum coke, the disposal of which often creates a serious refinery problem.

A novel process for conversion of high boiling hydrocarbons which overcomes the above difficulties is described and broadly claimed in my co-pending application Serial Number 720,271 filed 20 in the United States Patent Office, January 4, 1947, now abandoned. In that application the process described is broadly one wherein the hydrocarbon feed fraction bearing asphalt and oily constituents is contacted under suitable sorption conditions with a particle-form porous contact material which is suitable for sorbing the oily constituents of the feed in the pores of the contact material while leaving substantially unsorbed the asphaltic constituents of the liquid feed. A substantial separation of unsorbed asphaltic constituents from the contact material bearing sorbed oily constituents is then effected. The separated contact material bearing sorbed oily constituents is then heated to a temperature 25 suitable for effecting the desired conversion of the sorbed oily constituents. The present invention deals specifically with an improvement in the above described process wherein the contact material bearing sorbed oily constituents is heated 30 to a temperature suitable for conversion of the sorbed hydrocarbons by contacting it directly with a liquid heat exchange fluid such as a molten metallic alloy. The contact material after separation from the gaseous hydrocarbon conversion products and after separation from the liquid heat exchange fluid is subjected to regeneration 35 to prepare it for reuse.

40 A major object of this invention is the provision of a process for conversion of the oily constituents in high boiling asphalt bearing hydrocarbon fractions without the formation of prohibitive amounts of coke.

45 A specific object of this invention is the provision in a process wherein oily constituents from

asphalt bearing petroleum fractions are sorbed on a suitable porous sorbent, and then converted at higher temperatures in the presence of the sorbent and in the absence of the asphalt constituents of the petroleum fraction of an improved method for changing and controlling the solvent temperature during the conversion operation.

These and other objects of this invention will become apparent from the following discussion.

It has long been known that when porous adsorbents such as bauxites and natural and treated clays are contacted with liquid petroleum fractions, the asphaltic constituents may be adsorbed on the clay and thus removed from the oily constituents. Such a process is commercially employed for the decolorizing of mineral oils by percolation of the oils through clay-type adsorbents. The present process is the opposite of the so-called percolation and contact filtration processes for oil refining in that, by the present process, it is the oily constituent and not the asphaltic constituent which is sorbed by the contact material. This fundamental difference makes possible the combination cracking process of this invention and permits the elimination of the asphalt materials without contamination of the catalyst thereby. It has been found that porous contact materials, having a structure corresponding to that of an inorganic oxide gel having a sub-

5 The size of the sorbent particles employed in the process of this invention is to some extent dependent upon the variables involved in any particular application of the process. These important variables are time of contact between the liquid asphalt bearing charge and the sorbent in the sorption zone, temperature in the sorption zone, viscosity of the liquid charge, and to a lesser extent the ratio of liquid oil to sorbent charged to the sorption zone. Increasing time of contact and increasing temperature result in a decrease in the efficiency of separation of asphaltic and oily constituents. Decreasing viscosity of the liquid charge has the same effect. On the other hand increasing temperature and decreasing viscosity both result in more rapid sorption of the liquid oily constituents by the sorbent. If the ratio of sorbent to liquid charge is excessive some loss in separation efficiency results. By proper control of these variables some latitude in the average diameter of the sorbent employed may be provided. However when the diameter of the particles becomes too small, the sorbent preferentially adsorbs the asphaltic constituents from the liquid charge in the same manner as well known oil filtering clays. This is shown in Table I below in which is tabulated the deasphalting results obtained on Mid-Continent residuums using a silica-alumina gel type sorbent having a bulk density 10 15 20 25 30 in the 4-8 mesh size range of about 0.7.

stantially uniform porosity of low macropore volume with an average por diameter not exceeding about 125 Angstrom units and a particle size preferably larger than that corresponding to about 30 mesh (Tyler), have the ability to sorb the oily constituents of a liquid hydrocarbon fraction while leaving substantially unsorbed the asphaltic constituents. Natural and treated clays and bauxites such as are employed in oil filtering and decolorizing processes do not appear to have this property. The macropore volume of the contact material employed in the present invention should be relatively low so that the pore volume is mostly that of micropores. In general, the volume of macropores, that is, those pores having radii larger than 100 Angstrom units, should constitute less than about 30 percent of the total pore volume and preferably 10 percent or less. The measurement of pore size and pore size distribution in various porous materials is discussed in detail by L. C. Drake and H. L. Ritter in Industrial and Engineering Chemistry, Analytical Edition, volume 17, pages 782-791, 1945. The methods described there were essentially those employed in determining the bulk densities, average pore diameters, and other pore measurements of the adsorbents employed in the present invention.

It will be apparent from the above Table I that when the gel type sorbent particles were greater than 30 mesh size that even at relatively high temperatures and long contact periods the oily constituents of low viscosity and carbon residue were sorbed in the pores of the sorbent while the asphaltic constituents could be washed away with a suitable washing solvent, in this case benzol. On the other hand in the case of sorbent particles ranging from 30-60 mesh size, when the contact period was 24 hours (Experiment 4) or even 2 hours (Experiment 7) the sorbent acted similar to a normal filtering clay and preferentially adsorbed the asphaltic constituents. But when the contact time was reduced to two minutes (Experiment 5) the 30-60 mesh sorbent exhibited a preference for the oily constituents over the asphaltic constituents. When particle size was reduced below 60 mesh, the sorbent preferentially adsorbed the asphaltic constituents even at very low contact periods (Experiment 6).

The effect of contact time and temperature is shown in Table II below in which are presented the deasphalting results on an East Texas residuum having an original Saybolt Universal viscosity of 512 seconds at 210° F. and a Ramsbottom carbon residue of 11.1. In this experi-

ment a silica-alumina gel type sorbent of 4-8 mesh size and 0.48 bulk density was employed.

Sorbent to Oil Weight Ratio	1.6	1.4	1.5
Ramsbottom Carbon Residue, percent of sorbed oily constituents	1.9	2.6	2.0

In general it may be said that the particle size of the sorbent material particularly in the case of inorganic oxide gel type sorbents should be greater than that corresponding to about 60 mesh Tyler and preferably within the range about 0.022 to 1.0 inches average diameter. The best results may be obtained by limiting the sorbent within the range 0.03 to 0.20 inch average diameter and of reasonably uniform size. It is pointed out, however, that by proper control of the variables discussed hereinabove and also of the average pore diameter of the sorbent, operation according to the method of this invention may be obtained on sorbent particles outside the size ranges given although the results will be less satisfactory. It is contemplated that in its broader aspects this invention covers these latter operations as well as the operations within the specified preferred limits.

The porosity of the gel particles employed in the process of this invention is of fundamental importance. The degree of porosity is generally reflected in the bulk density of the gel composite used; the lower the bulk density, the greater being the degree of porosity. For the purposes of the present process, porous sorbent particles having bulk densities of between about 0.4 and 1.1 gram per cubic centimeter are preferred. The bulk densities indicated correspond to an average pore diameter of between about 20 and about 125 Angstrom units. Preferably, the sorbent used will have a bulk density between about 0.6 and about 0.8 gram per cubic centimeter. Gel particles having a bulk density greater than about 0.8 have been found to have excellent selectivity but poor sorbing capacity, while particles with a bulk density less than about 0.6 have relatively poor selectivity. However, since the selectivity of the deasphalting process improves with a decrease in temperature, particles with a bulk density less than 0.6 would be satisfactory for deasphalting stocks which can be processed at low temperatures.

The degree of porosity of a synthetic inorganic oxide gel will, in general, depend on the conditions under which it is prepared and allowed to set to gelation. A particularly convenient method of preparing gel particles used in the process of this invention is described in U. S. 2,384,946, issued September 18, 1945, to Milton M. Marisic. It is there disclosed that spheroidal particles of inorganic oxide gel may be prepared by mixing an acidic stream of sodium silicate and allowing the resulting sol to be ejected from a nozzle into an oil column, where the gel sets in the form of bead-like spheroids. The resulting gel spheres, after washing, drying and tempering, were of a size varying between about 4 and about 20 mesh. The gel beads so produced had a bulk density of between about 0.4 and about 1.1 and an average pore diameter of between about 20 and about 125 Angstrom units. They proved to be excellent selective absorbents for use in the process of this invention.

Likewise, irregularly shaped porous absorbent fragments or particles having the structure of inorganic oxide gels may be used. However, in general, spheroidal particles are to be preferred, since attrition losses are then at a minimum and contamination with gel fines of the asphalt-bearing stock is substantially eliminated.

In general, siliceous gel particles will be used in the process of this invention, such as silica gel, silica-alumina gel, silica-zirconia gel, silica-thoria gel, silica-magnesium oxide gel and the like. Porous sorptive silica glasses having a structure approaching that of a siliceous gel likewise are contemplated for use in the process described herein, it being necessary, however, that the porous glasses employed have an average pore diameter less than about 125 Angstrom units, and a macropore volume of less than about 30 percent of the total pore volume. The size of the porous glass particles must also be carefully controlled so as to obtain preferential sorption of the oily constituents. Usually particles of less than 60 mesh size are undesirable. It is also contemplated that within the scope of this invention other porous materials not of the inorganic oxide gel composition which have structures approaching that of a siliceous gel and are within the above specified pore size and particle size limits may be employed within the scope of this invention.

Typical of the porous glasses used are those described in U. S. 2,106,744, issued February 1, 1938, to Hood et al. There it is disclosed that a silica-alkali-boric oxide glass of suitable composition is prepared by a fusion process. Heat treatment of this glass results in separation of the glass into two phases; one phase is rich in alkali-boric oxide and is soluble in acids, while the other phase, which is insoluble in acid, consists of silica with a small amount of boric oxide. Extraction of this heat treated glass with acid results in a porous silica glass which can be employed as a porous absorbent separating medium in accordance with the present invention.

The liquid heat exchange fluid employed in this invention may be a suitable inorganic salt melt or preferably a molten metal or metallic alloy having a boiling point substantially above the highest temperature at which it is employed in the process and having a melting point substantially below the desired hydrocarbon conversion temperature. The heat exchange fluid should be oxygen-insensitive and should have a sufficiently high surface tension to avoid appreciable wetting of the contact material involved. It will be apparent that the proper choice of the heat exchange liquid will be dependent upon the particular conversion conditions and catalyst material involved in any given application of the invention. As an example, where the reaction involved is a catalytic cracking conversion of hydrocarbons occurring at temperatures of the order of 800-1000° F., molten lead or zinc may be employed or some metallic alloy having a melting point below about 750° F.-800° F. and having a low vapor pressure at 1000°-1100° F. An example of such an alloy is one consisting of 50 percent lead and 50 percent sodium which has a melting point of about 627° F. Exemplary of inorganic salt melts which may be employed when the reaction involved is catalytic cracking is cuprous chloride melting at about 788° F. The melting point of this salt melt may be reduced by the addition of alkali metal chloride in small amounts. For higher temperature reactions a suitable fluid is a mixture

7
of 50 percent lithium sulphate and the balance of approximately equal parts of the sulphates of sodium and manganese, which mixture melts at about 875° F. When the reaction involved is a low temperature treatment or molecular rearrangement of the sorbed hydrocarbons, a low melting point alloy may be employed such as a mixture of 50 percent tin and 50 percent lead melting at about 429° F.

The invention may be most readily understood by reference to the attached drawing which is a schematic arrangement of the system of this invention in which the apparatus is shown partially in section. In the drawing, vessel 20 is a deasphalting chamber which may be of rectangular or any other desired cross-sectional shape. A partition 24 across the upper section of chamber 20 defines a solid inlet surge chamber 25 in its upper end. Tubes 26 depend from partition 24 for flow of contact material from chamber 25 onto the surface of the substantially compact contact material column maintained in the sorption section 28 of the deasphalting vessel. Particle form contact material having a catalytic activity for the desired conversion and being suitable for sorbing the oily constituents of a liquid feed while leaving substantially unsorbed the asphalt constituents thereof is cooled to a suitable temperature in hopper 29 positioned above vessel 20 and then passed via conduit 21 into vessel 20 to keep replenished the column of such material in section 28 of vessel 20. A hydrocarbon feed stock which contains both asphaltic and oily constituents, for example a heavy petroleum residuum fraction or a tar separator bottoms fraction, is introduced into chamber 20 from manifold 10 via headers 11, closed on their ends, which extend into space 30 and nozzles 12 which are spaced along headers 11. The liquid charge distributes itself over the surface 27 of the contact material column and percolates downwardly within the column, whereby the oily constituents become sorbed in the pores of the contact material and the asphalt constituents remain substantially unsorbed. The contact material bearing sorbed oily constituents and the unsorbed liquid are withdrawn together from the bottom of vessel 20 through duct 22 at a suitable rate controlled by the valve 31.

The mixed liquid and solid material are directed by duct 22 onto an endless foraminous moving belt 14 supported over horizontally spaced pulleys 15 and 16, the latter of which is rotated by means of drive motor 17. The drain duct 22 and valve 31 therein may extend horizontally substantially the width of belt 14 so as to uniformly distribute solid material and liquid across the belt. Suitable guards (not shown) may be provided within chamber 35 along the opposite sides of the belt 14 to prevent solid particles from falling off the sides. A drain pan 18 is supported on its opposite sides from the wall of chamber 35 between the pulleys 15 and 16 and below the belt 14 so as to receive liquid which drains therethrough. The drained liquid containing the asphalt constituents is withdrawn from pan 18 via conduit 19 to the asphalt receiver 32. Entrained solid fines may be removed from the bottom of receiver 32 by means of outlet 33 and asphalt may be withdrawn via conduit 34 to pump 36. The asphalt containing liquid then may be entirely pumped from the system via conduits 37 and 38 or in part recycled via conduits 37 and 39 to inlet manifold 10 feeding the deasphalting chamber.

In some operations such recycling is desirable in order to reduce the amount of oily material in the finally discarded asphalt constituents to a minimum.

5 The contact material is carried along on belt 14 in the direction of the flow arrows and the contact material from which most of the unsorbed liquid has been separated by draining is discharged from the belt 14 into the washing 10 chamber 40. The chamber 40 communicates on its lower end with the boot section of a bucket elevator 43. In elevator 43 buckets 44 having perforated bottoms are moved upwardly and downwardly on endless chain 45 so as to transfer the washed contact material from the elevator 15 boot section upwardly to duct 350 feeding supply hopper 46 which in turn feeds the hydrocarbon convertor 47. The bottoms of the elevator buckets 44 are perforated, the perforations being 20 of such size as to retain the contact material particles while permitting liquid to pass therethrough. The elevator casing is inclined and the buckets are so shaped that liquid which drains from any given upwardly moving bucket 25 does not fall into the bucket moving upwardly therebelow, but is delivered back to the elevator boot section. A suitable washing solvent such as a naphtha, kerosene, benzol or light gas oil fraction may be introduced from an outside source 30 through conduit 42 into conduit 48 through which it passes into the elevator boot section. The solvent passes from the elevator boot section into the lower section of chamber 40 via passage 49 and then passes upwardly through the washing 35 chamber to be withdrawn from the upper portion thereof through conduit 50 to a washing solvent receiver 51. Baffles 52 provide a zig-zag passage in chamber 40 through which the contact material passes as it descends through the 40 bath of upwardly moving washing solvent. The solid particles are in this manner subjected to a quick wash under conditions so controlled as to accomplish the removal of asphalt containing liquid adhering to the outer surfaces of the contact 45 material particles without substantial separation of the sorbed oily constituents from the contact material. A relatively small amount of washing solvent may also be sorbed by the contact material during the washing operation. The 50 washed contact material may thus contain a substantial amount of sorbed oily constituents from the original feed, a relatively small amount of washing solvent (and in some cases practically no washing solvent) and in some instances small 55 amounts of asphalt constituents from the feed. It should be understood that while the gel type contact material particles of the type described have the unusual characteristic of sorbing oily constituents rather than asphalt constituents 60 from high boiling feeds, nevertheless, in the case of some feed fractions the gel type catalyst will also sorb relatively small amounts of asphalt materials. It has been found that this relatively small amount of sorbed asphaltic materials will not increase the coke deposits on the catalyst to prohibitive levels. It should be understood that in claiming this invention in the expressions "while leaving the asphalt constituents substantially unsorbed"; or contact material suitable for sorbing "substantially only the oily constituents of the liquid feed" and in like expressions the word substantially is intended to allow for these 65 relatively small amounts of asphalt constituents 70 which may in some operations be sorbed along 75

with the much larger amount of oily constituents in the contact material pores.

The washed contact material bearing sorbed oily constituents may be passed from the convertor supply hopper 46 into the upper end of convertor 47 as a substantially compact, elongated gravity feed leg flowing downwardly in conduit 55. Within the upper section of convertor 47 a horizontal partition 56 is positioned so as to define a seal chamber 57 in the upper end of the convertor. It is into this seal chamber 57 that the contact material feed is delivered.

A suitable inert seal gas such as steam or flue gas may be introduced into seal chamber 57 at a rate sufficient to maintain a gaseous pressure therein above that in the conversion section of vessel 47. Conduit 130, diaphragm valve 131 and differential pressure control instrument 132 are provided for this purpose. A plurality of uniformly spaced vertical conduits 58 serve as a passage for solid flow from seal chamber 57 onto the column 59 of contact material maintained in a lower section of the convertor. A horizontal liquid distributing plate 60 is positioned across the vessel 47 shortly above the lower ends of pipes 58. The plate 60 has therein a plurality of uniformly spaced orifices 61 which are of smaller diameter than the sorbent particles but of sufficient size to permit flow of liquid therethrough. Two header pipes 62 and 63 closed on one end thereof extend across the space 64 above pipes 58 and substantially above the plate 60. These pipes connect outside the vessel into heat exchange fluid inlet manifold 65 and have a number of nozzles 66 spaced along their length for delivery of liquid into the space 64 above plate 60. The liquid supplied from nozzles 66 passes through the orifices 61 and percolates down through the column 59. The rate of liquid heat exchange fluid supply is limited so as to maintain the column 59 in a non-flooded condition. The rate of liquid heat exchange fluid supply may be so limited either by proper design of the number and size of the orifices 61 or by throttling at valve 67 on manifold 65. A partition 68 is provided across the lower section of convertor 47 and a plurality of uniformly distributed pipes 69 depend from partition 68 for delivery of the used contact material and liquid heat exchange fluid into the drain chamber 70. The partition 68 is so shaped as to provide funnel shaped approach passages to each of the pipes 69 so as to avoid pockets of stationary solid material. The pipes 69 are of substantial length so as to provide a gas-solid disengaging space 85 above the bed of solids in the drain section. A gas outlet 86 connects into the vessel so as to communicate with space 85. The drain chamber 70 is of expanded cross-sectional dimension and is provided with a perforated bottom plate 71 which extends across chamber 70 at a slope greater than about 35 degrees. The top 74 of chamber 70 is substantially parallel to the plate 71. While the vessel 47 above the drain chamber 70 may be of circular or rectangular cross-sectional horizontal shape, the passage for solid flow along plate 71 as seen along line 2-2 should be preferably of rectangular shape. The orifices 72 in plate 71 are of sufficient size to permit the liquid heat exchange fluid to drain freely therethrough but of insufficient size to permit passage of sorbent particles therethrough. A vertical plate partition 73 depends from the top 74 of chamber 70 and terminates at a level above the plate 71 so as to provide a gas distributing

space 75 above the moving bed sorbent in the lower portion of the drain chamber. The partition 73 extends horizontally entirely across chamber 70 thereby providing a purge zone 150. A purge gas inlet pipe 76 connects into the top 74 above the space 75. A sorbent discharge pipe 82 connects into the lower end of purge zone 150 preferably a substantial distance above the plate 71. Below the plate 71 there is provided a closed sump chamber 80 having a bottom outlet 81.

In operation relatively cool contact material bearing sorbed oily constituents at a temperature of the order of 400-600° F., for example, is supplied onto column 59. A suitable hot liquid heat exchange fluid is supplied into space 64 from manifold 65. The heat exchange fluid exists at a temperature substantially above the desired hydrocarbon conversion temperature and its rate and temperature of supply are so controlled as to heat the sorbent to and maintain it within a suitable narrow range of hydrocarbon conversion temperatures. For example, molten lead may pass downwardly through orifices 61 onto column 59 at a temperature of about 1050° F. and at a rate sufficient to control a temperature of about 830° F. at the level of conversion zone drain pipes 69. The rate of lead flow is controlled below that which will flood the voids in the column 59 so as to leave adequate space for flow of liberated gaseous hydrocarbon products down through the column. The lead, sorbent and gaseous conversion products all pass through pipes 69 at the lower end of the conversion zone. The gaseous products are disengaged from the solid sorbent and liquid heat exchange fluid in space 85 and are withdrawn via pipe 86 to a suitable product recovery system 87 which may be of conventional type in the industry. In connection with the "gaseous products" it will be understood that the word "gaseous" as used herein in describing and in claiming this invention is intended in the sense of covering materials which are in the gaseous phase under the particular operating conditions involved regardless of the normal phase of those materials under atmospheric conditions. For example, gaseous conversion products leaving the convertor through circuit 86 at a temperature of the order of 800° F. to 950° F. and say 10 pounds gauge pressure may exist substantially entirely in the gaseous phase under these conditions although gasoline, gas oil and heavy fuel oil constituents may be present which are ordinarily liquids under atmospheric conditions. In drain section 70, the liquid heat exchange fluid settles from the bed of sorbent and passes through orifices 72 into sump 80. The sorbent is purged free of any residual gaseous hydrocarbons or liquid heat exchange fluid by the introduction of a suitable purge gas such as steam or flue gas via pipe 76. The purge gas passes down through the bed of sorbent and through orifices 72 and is removed from the upper portion of sump 80 via pipe 88. A suitable baffle 89 may be provided to prevent entrainment of liquid heat exchange fluid in the effluent purge gas stream. A body of liquid 90 is maintained within the bottom of sump 80 so as to prevent escape of gas through the heat exchange fluid outlet 81. The purged sorbent passes via pipe 82 to conveyor 95 by which it is transferred to duct 96 supplying the regenerator catalyst surge hopper 98. The rate of sorbent withdrawal from the purge zone 150 is controlled by a suitable flow control valve 102 on pipe 82. Lead now existing at a temperature of the order

of 825° F., for example, is pumped by pump 91 through pipe 92 to a heat exchanger 130 where it is again heated. The heated lead may pass via pipes 133, 134, 135 and 65 back to the convertor 47, or it may pass via pipes 133 and 136 to heater 137 wherein its temperature is further raised before it passes to the convertor via pipes 144 and 65. Alternately, the exchanger 130 may be bypassed entirely in which case the lead passes via pipes 92, 139, 134 and 136 to heater 137 and then via pipes 141 and 65 to convertor 47. Valves are provided on the above pipes to permit control of the lead flow in the manner described.

The used contact material which is supplied to the regenerator surge chamber 98 has lost a substantial part of its catalytic effectiveness due to the deposition of a carbonaceous contaminant thereon. The regenerator shown in the drawing is of the multi-stage variety which is described and claimed in application Serial Number 447,432, filed in the United States Patent Office June 17, 1942, now Patent No. 2,417,399, and application Serial Number 447,433, filed in the United States Patent Office June 17, 1942, now Patent No. 2,436,780, in which applications the present applicant is one of the applicants. In general the regenerator 97 is divided into a vertical series of alternating burning and cooling stages. Separate gas inlets 99, 100, 101 and 102 and separate gas outlets 104-107 inclusive spaced vertically from the inlets, are provided for the burning stages. The gas inlets are supplied by a combustion supporting gas such as oxygen, air or mixtures of air and flue gas, from inlet manifold 108. Flue gas passes from the burning stages through outlets 104-107 and is manifolded into outlet flue 109. Heat transfer tubes or coils may be suitably spaced within the cooling stages. Pipes 110 are inlets to these tubes and pipes 111 are outlets therefrom. The inlet pipes 110 connect into an inlet manifold 112 and the outlet pipes connect into an outlet manifold 113. The hot heat exchange fluid from manifold 113 passes via pipe 114 to heat exchanger 130 wherein it gives up its heat to the fluid entering via pipe 92. For example, heat exchange fluid from the regenerator existing at about 1050° F. may be cooled in exchanger 130 to about 830° F. The cooled fluid passes via pipe 145 to a cooler 146 wherein it is further cooled before passing via pipe 147, pump 117 and pipe 118 back to the inlet manifold 112. In this manner a large portion of the heat liberated on regenerating the sorbent material may be used for heating the sorbent within the convertor 47. The regenerator heat exchange fluid may take any of a number of forms such as a suitable gas under pressure or fused metallic oxides or mixtures of certain fused inorganic salts.

Hot regenerated contact material is withdrawn from the lower end of regenerator 97 through outlet 119 at the desired rate as controlled by throttle valve 120. The hot regenerated contact material is then transferred by conveyor 121 to hopper 29 where it is cooled to a temperature at which it may be reused in the deasphalting operation. The regenerated contact material in hopper 29 is cooled to a temperature suitable for its introduction into deasphalting chamber 20 by means of a suitable heat exchange fluid introduced at 68 and removed at 69. If desired, heat transfer tubes may be provided in both hoppers 29 and 46; and the heat exchange fluid withdrawn from the heat transfer tubes in hopper 29 via conduit 69 may be introduced into the tubes

in hopper 46 through conduit 70. The heat recovered from the final cooling of the regenerated contact material may thereby be utilized for partially heating the cooler, oily constituent bearing contact material in hopper 46. The heat exchange fluid, relieved of its heat in hopper 46 may be withdrawn from the tubes therein through conduit 71 and reintroduced into the tubes in hopper 29 through conduit 68. A pump 72 may be provided to cyclically circulate the heat exchange fluid and an exchanger 73 may be provided to permit any heat adjustments that may be required by the desired contact material outlet temperatures from hoppers 29 and 46. Heat may either be added or withdrawn by means of exchanger 73 as the particular operation involved requires.

While the system described hereinabove is one of the preferred forms of this invention, it should be understood that the various elements making up the particular combined system described are shown in highly diagrammatic form in the drawing and that the invention is not intended to be limited to the particular detailed construction of the various elements as shown. For example, while it is preferred to percolate the liquid charge downwardly through a column of the gel particles in the deasphalting chamber, nevertheless it is contemplated that within the scope of this invention the contacting of the gel particles and the liquid charge may be accomplished in a number of other ways and any method which permits the desired contacting is considered to be within the scope of this invention. For example, the liquid charge and the gel particles might be merely charged to a batch type mixer provided with suitable mechanical mixing devices and after suitable mixing has been accomplished, the material may then be discharged from the mixer to a suitable liquid solid separator. Likewise other methods and apparatus than that described hereinabove may be employed to effect separation of unsorbed liquid material from the contact material bearing sorbed oily constituents. For example, a rotary type filter provided with suitable means for accomplishing both filtering off of unsorbed liquid and washing of the contact material may be employed. In some operations the washing step may be eliminated entirely and the combination of draining and purging of the contact material with a suitable purging gas may be relied upon to separate the contact material from unsorbed asphalt containing liquid. Moreover, while in the system described hereinabove the washed contact material was partially heated and then charged through a gravity feed leg to the convertor, it is contemplated that the preliminary partial heating step may be eliminated and all of the heating accomplished within the convertor. Also suitable forced feed devices may be substituted for the gravity feed leg in less preferred forms of the invention as means of introducing the contact material bearing sorbed oily constituents into the convertor. It is also contemplated that the convertor and regenerator construction may be materially different from that shown in the drawing. Other suitable means for disengagement of gaseous products from the solid sorbent and the liquid heat exchange fluid may be employed. Also means other than that shown may be provided for accomplishing the separation of the heat exchange liquid from the used solid sorbent as will be apparent to those skilled in the art. The re-

generator may be of the single stage type or of other types known to the industry.

Since the contact material employed is preferably larger than 30 mesh size it is more practical and desirable in order to prevent undue attrition of the contact material to handle the contact material as a substantially compact moving bed or column in the convertor and regenerator and to convey it between vessels by continuous bucket elevators. However, within the broader scope of this invention it is contemplated that the contact material may move in suspension in the liquid heat exchange fluid in the heating and conversion zone and in the gaseous regeneration agent in the regeneration zone; and that means other than bucket elevators may be employed for transferring the contact material from one zone to another. It is further contemplated that within its broader scope the method of this invention may involve a substantially "in situ process" wherein the contact material remains permanently in one or more vessels. For example, the deasphalting, draining, washing, heating conversion and catalyst regeneration and cooling steps may be conducted in proper cycle in a single chamber in which the contact material particles remain as a fixed bed. In the case of operation of the latter type the contact material is heated by percolating a hot liquid heat exchange fluid through the fixed bed of sorbent bearing oily constituents until the desired conversion of the hydrocarbons has occurred. Thereafter the bed is purged substantially free of heat exchange fluid and a stream of air is passed through the bed to accomplish the regeneration. If desired a liquid heat exchange fluid may be percolated through the fixed bed during regeneration to remove the liberated heat. After the regeneration a separate heat exchange liquid may be percolated through the bed to cool it to a suitable temperature for the deasphalting step. Such an in situ operation may be conducted in a battery of side by side vessels containing fixed sorbent beds. The operation of the several vessels may be regulated so that a different step of the cyclic operation is being conducted in each vessel at any given time. The heat exchange fluid passing from a vessel in which the catalyst is being regenerated may be passed through the catalyst bed in a vessel in which the heating step is in progress, and from the latter vessel the heat exchange fluid may return to the bed undergoing regeneration. A batch type operation wherein the contact material is moved periodically, batch-wise from zone to zone is also contemplated.

It will be understood that the desirable conditions of operation during the deasphalting, washing, conversion and catalyst regeneration and cooling steps will vary depending upon the particular liquid charge stock involved and the conversion reaction involved and the particular conversion products desired. Certain general conditions of operation must, however, be observed. As regards the deasphalting operations the temperature at which the sorption of oily constituents by the particle-form gel type contact material is conducted should be high enough to give the oil sufficient fluidity to permit rapid sorption of the oily constituents but low enough to permit the contact material to function selectively. The maximum temperature maintained in the sorption zone is dependent on the viscosity of the stock being treated. The sorption of oily constituents becomes less selective as the viscosity

decreases. The desirable sorption temperature has been found to vary from below room temperature to about 500° F. depending on the liquid fraction treated. The temperature of the hydrocarbon liquid charged into the sorption zone and the contact material supplied thereto should be both adjusted to provide the desired sorption temperature. The contact material should not be permitted to contact the asphalt containing liquid feed at temperature at which substantial thermal coking of the liquid fraction would take place. This means that in general the contact material should be cooled in hopper 29 of Figure 1 for example, to a temperature which is at least below about 750° F. The pressure in the sorption zone may conveniently be within the order of atmospheric to 50 pounds per square inch. The residence time of the contact material within section 28 of chamber 20, i. e. the sorption zone, may vary from about 1-10 hours depending upon the liquid fraction involved, the temperature and the ratio of the contact material to the liquid charge. In many operations it is desirable to control the residence time of the contact material in chamber 20 by means of valve 31 such as will permit substantial saturation of the contact material with sorbed oily constituents.

The ratio of contact material to liquid charge to the deasphalting chamber may vary from about 0.5 to 20 parts by weight of contact material per part of liquid asphalt bearing charge and preferably from about 2 to 6 parts of contact material per part of liquid charge.

The amount of solvent employed in the washing operation may vary depending upon the characteristics of the solvent and of the unsorbed liquid involved. In general the contact material washing should be a relatively "quick wash" so controlled as to prevent removal by the solvent of substantial amounts of sorbed oily constituents from the contact material. The amount of solvent employed may be of the order of 0.25 to 2.0 volumes of solvent per volume of contact material. In some operations the purging step following the washing step may be omitted but when this step is employed the purging gas employed should be a gas which is not apt to cause oxidation of the oily constituents during the conversion, unless of course, the conversion process involved is a partial oxidation process. Steam, nitrogen, flue gas and low molecular weight hydrocarbon gases are suitable purging gases for most operations.

As an example of the separation obtainable in the deasphalting step of this process, the treatment of an East Texas crude bottoms fraction having an A. P. I. gravity of 15.0 at 60° F., a Saybolt Universal viscosity of 512 seconds at 210° F., a pour point above 115° F., and a Conradson carbon residue of 11.1 percent may be considered. The vacuum assay distillation of this feed fraction was as follows:

	°F.
I. B. P.	880
65	964
10%	1026
30%	1054
40%	1082
47%	1082

This feed fraction was contacted in a suitable confined chamber with a silica-alumina, spheroidal gel catalyst prepared by the method described in United States Patent 2,384,946 issued September 18, 1945 to Milton Marisic. The catalyst unpacked density was about 44 pounds per

cubic foot and consisted of particles falling within the range 4 to 16 mesh by Tyler standard screen analysis. The catalyst had been regenerated until the residual carbon thereon was below 0.5% by weight. During the operation the temperature was maintained at about 275° F. and the pressure was substantially atmospheric. The ratio of liquid to catalyst charge to the sorption zone was about 3.2 parts by weight of catalyst per part by weight of liquid charge. The residence time within the sorption zone was about 240 minutes. The unsorbed liquid was recycled until substantially all of the oily constituents had been removed therefrom. Finally a tar fraction amounting to about 30 percent by weight of the liquid charge was separated from the catalyst bearing sorbed oily constituents and the catalyst was washed with about half of its weight of Stoddard solvent, the residence time of the catalyst in the washing operation being limited to about 3 minutes. The catalyst after washing contained about 22 percent of its original weight of sorbed oily constituents which represented about 70 percent by weight of the original liquid charge. The catalyst bearing oily constituents was then heated to a temperature suitable for the cracking conversion of the sorbed oily constituents in a confined conversion zone. An analysis of the sorbed oily constituents before conversion was as follows: A. P. I. gravity 17.1; viscosity (K. V.) at 210° F.—46; pour point above 120° F., and Conradson carbon residue 5.7% by weight.

When the contact material bearing sorbed oily constituents is partially heated before introduction to the conversion zone as shown in Figure 1, it should be heated only to a temperature which is substantially below the desired conversion temperature. Usually a temperature of the order of 750° F. is the maximum temperature to which the contact material should be heated in hopper 46 of Figure 1. As has been pointed out, the contact material introduced to chamber 20 should be below about 750° F. so that regenerated contact material in hopper 29 of Figure 1 should be cooled to a level at least below about 750° F.

The operating conditions within the convertor 14 will vary depending upon the activity of the catalyst employed, the particular petroleum charge involved, the reaction involved and the products desired. In general it has been found desirable to maintain the pressures within a range varying from sub-atmospheric to about 200 pounds per square inch. Pressures of the order of 5 to 50 pounds per square inch gauge are preferred. The temperature for the conversion for cracking operations may vary from about 750° F. to 1100° F., temperatures of the order of 850 to 1000° F. being preferred where gasoline is the desired product. Where noncondensable gases are the principal desired product somewhat higher temperatures may be employed. The ratio of contact material to hydrocarbon throughput may vary from about 1.0 to 40 parts by weight of contact material per part of hydrocarbon charge.

The rate of liquid heat exchange fluid charge to the conversion zone will vary dependent upon the heat requirements of the particular operation involved. As an example, in the catalytic cracking of hydrocarbons an inorganic oxide gel catalyst having a density of about 40 pounds per cubic foot may be employed. The reaction temperature may be of the order of 850–1000° F. with the catalyst entering the conversion zone at

about 400° F. carrying about 30 percent by weight sorbed oil and leaving the conversion zone at about 850° F. Lead may be percolated through the catalyst bed at a rate within the range about 5 20 to 80 pounds of lead per pound of catalyst throughput, for lead supply temperatures of the order of 1200–950° F. respectively.

In the contact material regenerator, pressure of the order of atmospheric to about 100 pounds per square inch may be employed, pressures around atmospheric being preferred. The contact material temperature should be controlled below a heat damaging level by removal of heat therefrom during the course of the contaminant burning. The heat damaging level is that level 15 at which and above which the contact material suffers permanent loss in catalytic effectiveness for the conversion involved or loss in sorptive efficiency. The heat damaging temperature may 20 vary from temperatures above about 1150° F. to temperatures above about 1450° F. depending upon the particular gel type catalyst involved.

It should be understood that the details of 25 apparatus construction and arrangement, of operating conditions, and of applications of the process of this invention given hereinabove are intended merely as illustrative and it is not intended that the scope of this invention should be limited thereto or limited otherwise except as 30 it may be limited in the following claims.

I claim:

1. A process for conversion of oily constituents in asphalt bearing hydrocarbon liquid feeds which 35 comprises: contacting the hydrocarbon feed with a suitable solid sorbent material for sorbing the oily constituents, said sorbent being one in which more than about 70 percent of its pores are micropores, controlling the size of the sorbent particles and the contact time and temperature 40 and the relative amounts of liquid and sorbent contacted to effect sorption of the oily constituents into the pores of said sorbent while leaving substantially unsorbed the asphalt constituents, the size of sorbent particles employed being 45 larger for longer contact periods and higher contact temperatures, separating the sorbent bearing sorbed oily constituents from the unsorbed asphalt constituents, and contacting said sorbent directly with a hot liquid non-wetting heat 50 exchange fluid to heat said sorbent to a temperature suitable for the desired conversion of the oily constituents.

2. A process for conversion of high boiling oily constituents in asphalt bearing hydrocarbon fractions to lower boiling products which comprises: 55 contacting said liquid fraction for a suitable time and at a suitable temperature with a porous solid contact material in which the particle size is greater than about 60 mesh size and in which 60 most of the pores are micropores and the volume of pores having radii larger than about 100 Angstrom units is less than about 30 percent of the total pore volume to effect the sorption of the oily constituents of said feed in the pores of said 65 contact material while leaving the asphalt constituents substantially unsorbed; effecting a substantial separation of the unsorbed liquid from the contact material which bears the sorbed oily constituents, and passing a suitable hot, non-wetting liquid heat exchange medium into direct 70 contact with said contact material to heat it to a temperature suitable for conversion of said sorbed oily constituents to lower boiling products, separating the lower boiling hydrocarbon products 75 from said contact material and said liquid heat

exchange medium, separating said liquid heat exchange medium from said contact material, reheating said heat exchange medium and again passing it into contact with contact material bearing sorbed oily constituents.

3. A process for the conversion of the oily constituents of high boiling liquid asphalt containing hydrocarbon feeds which comprises: contacting said liquid feed for a suitable time and a suitable temperature for oily constituent sorption with a porous particle-form inorganic oxide gel-type contact material in which most of the pores are micropores and the volume of pores having radii larger than about 100 Angstrom units is less than about 30 percent of the total pore volume and in which the particles are greater than about 30 mesh size, to effect the sorption of the oily constituents of said feed in the pores of said contact material while leaving the asphalt constituents substantially unsorbed; effecting separation of the non-sorbed asphalt containing liquid from said contact material containing sorbed oily constituents, passing said contact material containing sorbed oily constituents through a confined conversion zone in admixture with a sufficient amount of hot liquid heat exchange fluid to heat it to a temperature suitable for the desired conversion of said sorbed oily constituents, said liquid heat exchange fluid being incapable of substantially wetting said contact material, separating converted hydrocarbon fluid products from said contact material and liquid heat exchange fluid, separating the used contact material from said liquid heat exchange fluid, passing said used contact material through a confined regeneration zone while contacting it with an oxygen containing gas to burn off contaminant deposits and thereby regenerate said contact material, cooling the regenerated contact material to a temperature suitable for its use in contacting said asphalt bearing liquid feed and reusing the cooled contact material for contacting asphalt bearing liquid feed as aforesaid, heating the liquid heat exchange fluid after its separation from said used contact material and returning the heated liquid heat exchange fluid to said conversion zone to heat said contact material as aforesaid.

4. A process for conversion of high boiling oily constituents in asphalt bearing hydrocarbon fractions to lower boiling products which comprises: contacting said liquid fraction with a porous particle form inorganic oxide gel-type catalyst in which most of the pores are micropores and the volume of pores having radii larger than about 100 Angstrom units is less than about 30 percent and in which the particles are greater than about .022 inch average diameter to effect sorption of the oily constituents of said fraction in the pores of said catalyst while leaving the asphalt constituents substantially unsorbed, effecting separation of said catalyst bearing sorbed oily constituents from the non-sorbed asphalt constituents, passing said catalyst bearing sorbed oily constituents downwardly through a confined conversion zone as a substantially compact column, passing a hot liquid heat exchange medium downwardly through said column at a rate insufficient to flood the voids in said column but at a temperature and rate sufficient to heat said catalyst to a temperature suitable for conversion of said oily constituents to lower boiling gaseous products, said heat exchange medium being incapable of substantially wetting said catalyst, withdrawing said gaseous products from said con-

version zone, separating the liquid heat exchange medium from the used catalyst upon which a carbonaceous contaminant has been deposited, passing the used catalyst through a confined regeneration zone while contacting it with a combustion supporting gas to burn off said carbonaceous contaminant, controlling the temperature of said catalyst below a heat damaging level in said regeneration zone, cooling the regenerated catalyst to a temperature suitable for its use in contacting said asphalt bearing liquid fraction, re-using the cooled catalyst for contacting said asphalt bearing liquid as aforesaid, heating the liquid heat exchange medium after its separation from said used catalyst to a temperature substantially above the desired hydrocarbon conversion temperature and returning said heated liquid heat exchange medium to said conversion zone.

5. A process for conversion of the oily constituents present in a liquid hydrocarbon feed stock containing both oily and asphaltic constituents at elevated temperatures in the presence of a particle-form contact mass material which process comprises: contacting the liquid charging stock in a confined deasphalting zone with a particle-form porous contact material having the pore structure of an inorganic oxide gel in which the total pore volume is taken up mostly by micropores, there being less than about 30 percent pores having radii larger than about 100 Angstrom units, the contact material being made up substantially of particles larger than about 30 mesh size; controlling the temperature during the contacting at a level suitable for the sorption of oily constituents in the pores of the contact material and below that which would cause substantial coking of the asphalt constituents, which constituents remain substantially unsorbed in the pores of said contact material; effecting separation of the contact material bearing sorbed oily constituents from the unsorbed constituents of said hydrocarbon feed stock; passing the separated contact material bearing sorbed oily constituents downwardly as a substantially compact column through an elongated, confined substantially vertical conversion zone to effect conversion of said oily constituents to lower boiling gaseous products; passing a hot liquid heat exchange medium downwardly through said column at a rate below that which would flood the voids in said column, said heat exchange medium being incapable of substantially wetting said contact material, controlling the supply rate and temperature of said liquid heat exchange medium to effect heating of said contact material to a temperature suitable for said hydrocarbon conversion, separating the gaseous products from said contact material and liquid heat exchange fluid, separating the used contact material upon which a carbonaceous deposit has formed from the liquid heat exchange fluid, passing the used contact material through a confined regeneration zone while contacting it with an oxygen containing gas to burn off said carbonaceous contaminants, passing a second fluid heat exchange medium in heat exchange relationship with said contact material in said regeneration zone to remove the heat liberated by said contaminant burning, effecting an exchange of heat from said second heat exchange medium to said first heat exchange medium which has been separated from said used contact material, thereby heating said first heat exchange medium to a temperature substantially above the average conversion temperature in said conversion zone, 75 returning said first heat exchange medium to

said conversion zone, cooling the regenerated contact material to a temperature suitable for sorption of said oily constituents and re-using it in said deasphalting zone as aforesaid.

6. A process for conversion of high boiling oily constituents in asphalt bearing hydrocarbon fractions to lower boiling products which comprises: contacting said liquid fraction with a porous particle form inorganic oxide gel-type catalyst in which most of the pores are micropores and the volume of pores having radii larger than about 100 Angstrom units is less than about 30 percent and in which the particles are greater than about .022 inch average diameter to effect sorption of the oily constituents of said fraction in the pores of said catalyst while leaving the asphalt constituents substantially unsorbed, effecting separation of said catalyst bearing sorbed oily constituents from the non-sorbed asphalt constituents, passing said catalyst bearing sorbed oily constituents downwardly through a confined conversion zone as a substantially compact column, introducing a molten metal heat exchange medium into the upper section of said conversion zone at a temperature substantially above the desired average hydrocarbon conversion temperature, percolating said heat exchange medium downwardly through said column at a rate sufficient to heat it to a temperature suitable for conversion of said oily constituents to lower boiling gaseous products, and withdrawing the gaseous products, used catalyst and heat exchange medium from the lower section of said conversion zone.

7. A process for conversion of high boiling oily constituents in asphalt bearing hydrocarbon fractions to lower boiling products which comprises: contacting said liquid fraction with a porous particle form inorganic oxide gel-type catalyst in which most of the pores are micropores and the volume of pores having radii larger than about 100 Angstrom units is less than about 30 percent and in which the particles are greater than about .022 inch average diameter to effect sorption of the oily constituents of said fraction in the pores of said catalyst while leaving the asphalt constituents substantially unsorbed, effecting separation of said catalyst bearing sorbed oily constituents from the non-sorbed asphalt constituents, passing said catalyst bearing sorbed oily constituents downwardly through a confined conversion zone as a substantially compact column, passing a hot liquid heat exchange medium downwardly through said column at a rate insufficient to flood the voids in said column but at a temperature and rate sufficient to heat said catalyst to a temperature suitable for conversion of said oily constituents to lower boiling gaseous products, said heat exchange fluid being incapable of substantially wetting said catalyst, withdrawing the used catalyst, gaseous products and liquid heat exchange medium from the lower section of said

conversion zone, separating said gaseous products from the catalyst and liquid heat exchange medium, draining the liquid heat exchange medium from said catalyst and finally purging said catalyst with a suitable inert purge gas, passing the purged catalyst through a confined regeneration zone while contacting it with an oxygen containing gas to burn off from the catalyst carbonaceous contaminants deposited thereon in said conversion zone, cooling the regenerated catalyst to a temperature suitable for its use in sorbing oily constituents and re-using the cooled catalyst for contacting said asphalt bearing fraction as aforesaid, passing the liquid heat exchange medium drained from said used catalyst through a heating zone to heat it to a temperature substantially above the average hydrocarbon conversion temperature in said conversion zone and returning the heated heat exchange medium to the upper section of said conversion zone.

8. A process for conversion of oily constituents in asphalt bearing hydrocarbon liquid feeds which comprises: contacting the hydrocarbon feed with a porous, particle form solid sorbent in which most of the pores are micropores and the volume of pores having radii larger than about 100 Angstrom units is less than 30 percent of the total pore volume and having an average particle diameter greater than that corresponding to about 60 mesh Tyler, controlling the contact time and temperature and the relative amounts of liquid and sorbent contacted to effect sorption of the oily constituents into the pores of said sorbent while leaving substantially unsorbed the asphalt constituents, separating the sorbent bearing sorbed oily constituents from the unsorbed asphalt constituents, and passing a hot preheated molten metal directly into contact with said contact material to heat it to a temperature suitable for the desired conversion of said sorbed oily constituents.
